MEANS FOR TEACHING MARKSMANSHIP

Filed Jan. 5, 1932

WITNESS:

Bob Pritchel

UNITED STATES PATENT OFFICE

CHARLES SCHWARTZ, OF LAWRENCE TOWNSHIP, MERCER COUNTY, NEW JERSEY

MEANS FOR TEACHING MARKSMANSHIP

Application filed January 5, 1932. Serial No. 584,763.

Objects of the present invention are to facilitate instruction in marksmanship with trigger fired arms; to provide for overcoming defects in marksmanship due to the pupils flinching or other involuntary nervous movements or muscular contractions; to permit the student or pupil to call or designate his aim in respect to the target after the weapon has been fired or discharged; and, in general, to improve marksmanship and the teaching thereof.

Other objects of the invention will appear from the following description at the end of which the invention will be claimed.

15 Generally stated, the invention comprises the dual control of the firing of a trigger fired weapon, one control being exercised by the pupil or student, and the other by the instructor, as will be more fully described.

20 The invention also comprises the improvements to be presently described and finally claimed.

In the following description reference will be made to the accompanying drawing forming part hereof and in which

Figure 1 is a side view with parts broken away of a fire arm embodying features of the invention, and

30 Fig. 2 is a side view illustrating the application of the invention to another type of fire arm.

Referring to Fig. 1, the trigger 1 is free for manual operation by the pupil and the fire arm is provided with means or mechanism operable by the instructor and adapted to actuate the trigger. Electrical means are selected for illustration, and they comprise an electromagnet mounted in the fire arm, and a control 2 independent of the fire arm. The 35 core 3 of the electromagnet when energized operates the trigger 1 and fires the weapon. As shown in Fig. 1, the electromagnet is housed in a chamber provided in an enlargement 4 of the grip and is supported by arranging one end of its cores through a hole in the trigger guard 5 with one end of the spool of the winding 6 in contact with the guard 5. The other end of the core 3 is provided with a pointed screw 7 which takes into 45 a pit in the handle 8 of the weapon or re-

volver. 9 indicates a source of current, such as a portable battery, and from it extend leads 10 and 11 provided with a terminal plug 12 for connecting and disconnecting them with coil 6 of the magnet. The control is interposed in the lead 10 and may serve like a push button to open and close it. The enlargement 4 may consist of insulating material and if it is notched, as shown at 13, for the accommodation of the fingers of the student or pupil, it induces a proper movement in pressing the trigger. The described equipment may be applied to any trigger weapon.

The mode of operation may be explained as follows:

It is not difficult for the instructor to teach the pupil or student how to aim the weapon, but the difficulty is in large part that the pupil or student flinches and in that way renders a correct aim futile. By the present invention after the student or pupil has had an opportunity to aim the weapon and without the knowledge of the student or pupil and before the latter has had time to flinch or make involuntary movements and so spoil the aim, the instructor by means of the control 2 fires the weapon usually with the result that a good shot is made. This not only encourages the pupil but also demonstrates to the pupil that miss or bad shots are due to flinching so that the pupil acquires confidence in his ability to aim a weapon and learns to avoid flinching and like errors.

The construction and mode of operation of the modification illustrated in Fig. 2 are substantially as described with the exception that the core 3^a of the magnet operates through a centrally pivoted lever 14 and can be arranged in advance of the trigger of, for example, a gun as diagrammatically illustrated in Fig. 2.

It will be obvious to those skilled in the art to which the invention relates that modifications may be made in details of construction and arrangement and matters of mere form without departing from the spirit of the invention which is not limited to such matters or otherwise than the prior art and the appended claims may require.

I claim:

1. For teaching marksmanship, a detached fire arm free to be held in the hand for manual aiming and having a trigger free for manual operation by a pupil and provided with means carried by the fire arm and operable by an instructor and adapted to actuate the trigger.
2. For teaching marksmanship, a detached fire arm free for manual aiming and having a trigger and provided with a dual firing control carried by the fire arm and operable by the instructor and by the pupil.
3. A detached fire arm free for manual aiming and having a trigger free for manual operation, an electromagnet carried by the fire arm and for operating the trigger, and electrical connections for the electromagnet.
4. A fire arm having a trigger and trigger guard and provided with a chamber, an electromagnet arranged in said chamber and having its core projecting through the trigger guard, and electrical connections for the electromagnet including a circuit controller.

CHARLES SCHWARTZ.
